2,289,025

DERIVATIVE OF 2,5-DIAMINO-1,4-BENZOQUINONE

Gerhard Langbein, Hofheim in Taunus, Germany,
assignor to General Aniline & Film Corporation,
a corporation of Delaware

No Drawing. Original application November 29, 1938, Serial No. 242,919. Divided and this application July 26, 1941, Serial No. 404,152. In Germany December 4, 1937

1 Claim. (Cl. 260—396)

The present invention relates to a new derivative of 2,5-diamino-1,4-benzoquinone and more particularly to the compound obtainable by condensing 2 mols of 2-methoxy-5-(para-diphenyl)-amino-3,6-dichloro-1,4-benzoquinone with 1 mol of para-phenylene-diamine.

The condensation is preferably performed by heating the components in a diluent, such as an organic solvent and, if desired, in the presence of an acid binding agent.

A mixture of 37.4 parts of 2-methoxy-5-(para-diphenyl)-amino-3,6-dichloro-1,4-benzoquinone, 1000 parts of n-butanol, 4.5 parts of para-phenylene-diamine and 8.5 parts of sodium acetate is heated to boiling for 4 hours. The mixture is filtered with suction, while hot, and the solid produce obtained is washed with butanol, alcohol and water. The brown diaryl-amino-1,4-benzoquinone containing two quinone nuclei dyes wool in a colorless vat intense black-brown tints. It has the following probable constitution:

This application is a division of application Serial No. 242,919, filed November 29, 1938.

I claim:

The compound of the formula:

The following example serves to illustrate the invention, but it is not intended to limit it thereto; the parts are by weight:

being a brown product which dyes wool in a colorless vat intense black-brown tints.

GERHARD LANGBEIN.
